GAME PRACTICE MEANS

Carl I. Robinson, Chicago, Ill.

Application October 15, 1932, Serial No. 638,020

5 Claims. (Cl. 273—29)

This invention relates to improvements in game practice means.

An object of the invention is to provide means whereby the rebound of a ball from a vertical surface against which it is projected will be indicated thereon or on a horizontal foreground or foreground so that the player can determine whether the ball would have alighted within predetermined boundaries had its flight been uninterrupted by the vertical surface. The principles of the present improvements can best be described by reference to means for practicing the game of lawn tennis and embodiments of my game practice means adapted for practicing such game are selected for illustrating the invention.

Thus, in the employment of my invention for practicing the playing of tennis, the practice means enables the player to practice from service positions, fixed volley positions, and catch-as-catch-can positions governed by the rebound of the ball when projected against a vertical ball returning member.

Certain advantages of the principle of the invention can be obtained by the utilization only of a vertical ball returning surface occupying the plane of a tennis net, which surface is provided with horizontally defined zones into any one of which a ball, if driven with less than a pre-determined velocity, will be fair, that is, such ball in actual play would have alighted within the rear limits of a court. Such a vertical surface having the described horizontal zones may also be employed in connection with a foreground having transverse zones so correlated with respect to the other zones that the rebound of the ball will indicate whether the velocity of the ball was such that in actual play it would have fallen within or without the end or side limits of a court.

Another object of the invention is to provide either or both foregrounds and bounding or ball return surfaces with suitable boundary or zone markings or other indicia to assist the player in noting the accuracy with which he hits the ball with respect to the height or its direction toward any desired area, such as a particular portion of a tennis court.

Other objects relate to various features of arrangement of details which will be apparent from a consideration of the following specification and accompanying drawings wherein:

Figure 1 is a diagrammatic side view of a tennis court suitably modified for the purposes of illustrating the principles of my invention.

Figure 2 is a top plan view thereof.

Figure 3 is a perspective view illustrating a

foreground of reduced dimensions in conjunction with a ball return surface, beyond which in dotted lines is shown the opposite portion of an actual court.

Figure 4 is a perspective view of practice means showing the foreground and the ball return surface provided with transverse zones for noting the height at which a ball strikes said surface and its rebound therefrom to the foreground.

Figure 5 is a view of a practice device for use in practicing the placing of a ball at or adjacent a certain designated portion of an imaginary court.

Figure 6 is an enlarged view of one form of chart for use with the practice means shown in Figure 5.

Figure 7 is a broken elevation of a modified form of ball return surface.

In Figure 1 of the drawings, tennis court sections 10 and 11 are shown in side elevation provided with a net 12. If a player serves a ball from the point A which would have the course of the line B and strike the court 10 at point C, a bounding board, or other vertical ball return surface 13 placed in the plane of the net, will return the ball along the dotted line D to the point E on the court 11. If the point C is within the service area of court 10, it will be apparent that the court 11 can be so dimensioned and arranged that the point E will be in the same relative position in court 11 that point C is in court 10. Since the ball in striking the board or surface 13 will not rebound as far into court 11 as it would have gone had its flight been not intercepted, the court 11 may be foreshortened so as to indicate to a player who drives the ball against such ball return surface the position at which the ball would have alighted in a court 10 in actual play.

Thus, for example, in Figures 1 and 2 the court is shown foreshortened longitudinally approximately 19%, and transversely about 8% with reference to court 10. Line F indicates another course of a ball from the same point A to landing point G while dotted line H shows the path of rebound from the surface 13 to the point I of court 11.

In Figure 2 I have shown a board or surface 13 having an imaginary court 10 on one side and a foreshortened court or foreground 11 on the side on which the player stands. If the player serves the ball from the point J and its course in actual play would be that indicated by the line K and its landing point L, the return surface 13 will cause the ball to rebound approximately along the dotted line M and strike the foreground 11 at point N which point bears substantially the same

relative position in the foreground 11 as point L bears to the imaginary court 10.

In Figure 3 a perspective view of this arrangement is illustrated, the actual foreground 11 being shown in connection with a vertical return surface 13 which may be the wall of a room or any other suitable structure. The lower portion of the surface 13 has been provided with the representation of a net 12 or it may be indicated merely by a horizontal line indicating the upper limit of a net. If a player wishes to practice serving he may take any conventional serving position, such as the serving position marked J. To serve the ball against the surface 13 so that the ball would land within lateral limits of an actual court, the ball must strike the surface 13 between the vertical lines 14, 15, which may be painted on the surface 13 or on a sheet of material, such as canvas for example, secured to the surface 13. The player will know that his ball must strike the surface 13 within the lines 14, 15 if it in actual play would have been a fair serve. It may strike within the lines 14, 15 and not be a good serve since if it strikes too high or is too swift, or is too close to the line or margin 15 at a point well above the net, the ball on its rebound will not fall within the service area, 11a of the court 11 and the player will thus know that such serve in actual play would not have been within the prescribed limits.

For practicing serving from other points, the lines 14, 15 must be changed with reference to the foreground 11. This may easily be accomplished if such boundary lines are formed by means of tapes suspended from the upper portion of the ball return surface or are made on a sheet of material removably secured to the surface 13. The same result may be accomplished also by shifting the foreground 11 if it be formed of a sheet of canvas or the like detachably secured to a floor.

The foregoing description showing the relation of a foreshortened foreground to an imaginary opposite court with an interposed ball return surface explains the principle of the invention. To obtain advantage of practice by the use of a return surface and foreground, it is not necessary that the foreground be marked off in simulation of a tennis court. The principle of my improvement can be utilized by the arrangement shown in Figure 4, wherein the vertical ball return surface 16 is provided with defined horizontal zones and the foreground 17 is provided also with correlative zones. In this figure the zones of the return surface are numbered and lettered as shown, while the zones of the foreground are lettered. The return surface has vertical limit lines 18, 18 between which a ball must strike to fall within the lateral limits of the above mentioned imaginary court, or of an actual court in actual play. If a ball strikes the space or zone marked 3 on the surface 16, and on bounding to the foreground strikes any place between the base of said surface and the rear limit of zone D of the foreground, he will know that said ball in actual play would have landed within the end boundary of his opponent's court. The letters on the surface refer to the letters on the foreground and a ball that rebounds beyond a zone identified by such corresponding letter was driven too hard with reference to its height above the net to alight within the end limit of an actual court. Other systems of correlating the two sets of graduation may be employed, thus the numeral 75 of the surface 16 may be omitted or numerals

used only on both the return surface and the foreground.

A vertical ball return surface such as the surface 16 shown in Figure 4 may be used for certain practice also without the foreground. Thus, the ball return surface may be provided with horizontally defined zones which serve to register the height of the ball. If a player knows that a ball of maximum velocity must strike the lower-most zone to alight within his opponent's court in actual play, he can utilize such a ball return surface for measuring the height of the ball and thus by practice become proficient in keeping the fast balls low but above the net. Similarly, a ball which strikes in a higher zone must be a slower ball to be fair in an opponent's court, while a ball which strikes in the uppermost zone must be of minimum velocity. Thus a player can practice driving the ball at various velocities and by noting the zone at which a ball is intercepted by the return surface, can determine the maximum height which a ball of a given velocity may have as it passes over a net in actual play. By this method of practice, the player can measure the flight or gauge the ultimate objective of the ball with reference to the end or side limits of an actual court.

In Figure 5 the foreground 19 and the vertical return surface 20 are provided with the designated correlative areas shown. In the use of this arrangement the player may refer to the chart 21 shown in Figure 6, which in actual practice may be placed at any convenient position, as on the vertical surface as illustrated in Figure 5. This chart represents a court marked off in numbered rectangles. Suppose a player wishes to practice driving a ball into any of the areas of his opponent's court designated on the chart. For example, if a ball strikes the designated area 37 of the return surface, having been served along the dotted line 22 from the service position 23, its path on the rebound may be along the dotted line 24. The distance it rebounds from the area 37 will be dependent on its velocity, and hence if the ball alights in one of the foreshortened areas in the foreground, which bears a number or legend corresponding to an area of the chart which lies within the service court, the player will know that the serve would have been within the prescribed limits in actual play. Thus a ball rebounding from the area 37 of the ball return surface into any of the areas 98, 90, 82, 74, 66, 58 or 50 of the foreground, is found by reference to the chart of Figure 6, to be within the limits of the service court. It will be seen that the projection 25 of the line 22 passes through similarly designated areas on the imaginary half court 26, such projection 25 indicating the course the particular ball would have taken in actual play.

The areas of the ball return surface may have thereon, in addition to the identifying numeral of each particular area, indicia indicating the areas of the foreground within which a ball must strike on its rebound in order to be fair. Thus in Figure 7 which illustrates a fragment of such modified return surface, the area numbered 37 contains the above mentioned area designating numerals indicating the course of a typical service ball and also the numerals indicating areas of a volley ball which is returned from the arbitrarily selected position 27 and the flight of which is indicated by the line 28. This ball is assumed to strike the area 37 of the return surface 20 and to rebound along the line 29. The lines 24

and 29 indicate that the balls were driven with the maximum velocity possible to alight within the respective limits of the court.

By the use of differently correlated foregrounds 5 and ball return surfaces or charts, practice from other positions is possible, the player being able to note the accuracy of his serves or volley returns both as to direction and velocity.

If desired, the foreground may be provided with 10 a service line 30 and a base line 31 for indicating the rear limits of the court for service and volley play respectively. It may also be provided with the dash lines 32, 33 and 34 which indicate lateral limits of the service courts.

15 From the above description it will be seen that by means of the present improvements the player can practice the various "shots" from different positions and at various speeds and by reference to the ball return surface, or the foreground or 20 to both, can determine whether the ball would have alighted within prescribed limits in actual play.

Further modification of the markings or graduations or zones of either or both the return surface and foreground may be made in accordance 25 with the principles of my invention for practicing unusual serves or returns, but the above described embodiments will serve to illustrate the present improvements since they are capable of 30 use with the serves or returns commonly used in ordinary play, including "hooked" or curved balls.

The ball return surfaces and foregrounds above described may be made directly on suitable walls 35 or floors, or if they are made on sheets of material, such as canvas, they will preferably be detachably connected to the respective areas by any appropriate means, such as by eyelets 35 shown in Figure 4 for the purpose of illustration only.

40 Other modifications and refinements of the improvements herein disclosed may suggest themselves to those skilled in the art such as, for example, adjusting a removable foreground toward or away from the ball return surface when 45 balls are employed having lesser or greater resilience or rebounding characteristics than an average ball for use with which the spacings of the zones of the foreground were designed, but it will be understood that the above disclosures 50 have been selected for the purpose of illustrating the principles of the invention and I, therefore, do not wish to be restricted to the specific embodiments of the invention above described except as so limited by the appended claims.

55 I claim:

1. Tennis practice means comprising a vertical ball returning surface corresponding in position to the plane of a tennis net and against which a

ball may be projected, said surface having vertical boundary markings thereon for indicating the side limits of an imaginary full size conventional tennis court beyond said surface, a foreground upon which said ball rebounds from said vertical surface, and boundary markings on said foreground foreshortened with respect to relative markings of a full size court to compensate for the reduced flight of a rebounding ball for indicating the position where said ball would have alighted with respect to prescribed limits in actual play.

2. Tennis practice means comprising a vertical ball returning surface corresponding in position to the plane of a net and against which a ball may be projected, a foreground upon which said ball rebounds from said vertical surface, indicia on said surface for indicating particular areas of an imaginary court at the rear side of said surface, and indicia on such foreground for indicating positions where a ball rebounding to the same from said surface would have alighted with reference to any such area in actual play.

3. Tennis practice means comprising a vertical ball-intercepting surface corresponding in position to the plane of a tennis net and having a plurality of defined rectangular areas thereon, a horizontal foreground having rectangular areas defined thereon, and indicia for correlating the areas of said surface and foreground for determining the objective of a driven ball with respect to an actual court when the ball strikes within one of said areas of said surface and rebounds therefrom to one of said areas of said foreground.

4. Tennis practice means comprising two removable sheets having defined zones thereon, one adapted for attachment to a vertical wall corresponding in position to the plane of a net and the other to a horizontal foreground in front of said wall whereby the objective of a ball driven against said vertical sheet and rebounding to said horizontal sheet can be determined with respect to prescribed limits of an actual court.

5. Tennis practice means comprising a vertical ball returning surface corresponding in position to the plane of a tennis net and against which a ball may be driven, a forefield upon which a ball may rebound from said surface and rebound in turn from said forefield to enable the same again to be driven against said surface as in conventional play, and markings on said forefield defining tennis court areas foreshortened in width and length for indicating whether a ball rebounding thereto from said surface would have alighted within prescribed limits in actual play.

CARL I. ROBINSON.
